UNITED STATES PATENT OFFICE

LEO GOODKIND, OF WOODMERE, NEW YORK

DESIGN FOR A BOUDOIR SLIPPER

Application filed March 3, 1931. Serial No. 38,913. Term of patent 3½ years.

To all whom it may concern:

Be it known that I, LEO GOODKIND, a citizen of the United States, residing at Woodmere, Long Island, county of Nassau, State of New York, have invented a new, original, and ornamental Design for a Boudoir Slipper, of which the following is a specification, reference being had to the accompanying drawings, forming a part thereof:

Fig. 1 is a plan view of a boudoir slipper, showing my new design, and Fig. 2 is a side perspective view of the same.

The dominant feature of the design resides in the ornamental appearance of the slipper as produced by the wide overlapping elements in the manner as shown.

I claim:

The ornamental design for a boudoir slipper substantially as shown and described.

LEO GOODKIND.
